COUNTING CIRCUITRY EMPLOYING MULTI-CATHODE GLOW TRANSFER TUBE AND A.C. BIAS SOURCE TO INCREASE CIRCUIT STABILITY

Charles B. Falconer, Newton, Mass., assignor to Laboratory for Electronics, Inc., Boston, Mass., a corporation of Delaware

Filed Oct. 4, 1962, Ser. No. 228,385

2 Claims. (Cl. 315—84.6)

This invention relates in general to gas discharge tubes and in particular to a new and improved technique for increasing the reliability and stability of counting circuits which include glow transfer tubes.

Many of the commonly used counting circuits employ glow transfer tubes as their basic counting element. In such a tube, a glow discharge occurs between a central anode and one of several cathodes, usually ten, which encircle the anode. By the application of a sequence of pulses for each count, the discharge is transferred to the next adjacent cathode. The current surge arising from each such discharge flows through a cathode resistor which must develop a voltage sufficient to operate the following circuits. If the voltage developed across the cathode resistor is too large, instabilities arise in the glow transfer tube and cause the discharge to jump spuriously from one cathode to another. In a counting circuit such transfer errors can be extremely serious. This problem is felt most acutely in readout circuits which employ, in addition to the glow transfer tube, a series of individual gas discharge tubes, such as neon lamps, in the cathode circuits of the glow transfer tube to indicate the position of the count. An example of such a circuit may be seen in Patent No. 2,985,794, issued to E. R. Sarratt on May 23, 1961.

Although a D.C. bias is usually applied to place the neon lamps near their maintaining potential, the voltage developed across the cathode resistor of the glow discharge tube must still be sufficiently large to reach the striking potential of the neon lamp in order to turn it on. At the same time, this voltage must be kept sufficiently low so that instabilities and spurious transfers do not occur in the glow transfer tube. Since the D.C. bias of the neon lamps must be kept below the minimum maintaining potential and the voltage developed across the cathode resistor of the glow transfer tube plus the D.C. bias must reach the maximum striking potential of all the neon lamps in the set, the neon lamps must be closely matched with each other so that the required voltage swing may be minimized. While, in some cases, a matched set of neon lamps may be obtained, which does allow the voltage swing to be kept within reasonable limits, such a set is extremely costly. In addition, there are usually six decades, that is, six glow transfer tubes each with associated circuitry including a series of neon lamps in a counting circuit, and hence the problem of matching each set to every other set is encountered, thereby greatly increasing the rejection rate and the overall cost.

It is, therefore, a primary object of the present invention to provide a new and improved technique whereby the signal voltage developed across each cathode resistor in a glow transfer tube circuit utilizing neon lamps may be reduced, thereby eliminating the possibility of spurious transfers.

It is another object of the present invention to reduce the necessary D.C. voltage swing between the minimum maintaining potential and the maximum striking potential in a group of neon lamps, thereby resulting in a lower rejection rate.

It is a further object of the present invention to pro-

vide means for reducing the signal voltage necessary to operate a gas discharge tube.

Broadly speaking, the present invention provides for the application of a continuous A.C. voltage to the neon lamps in the readout circuit of a glow transfer tube. Under these conditions, the maximum D.C. voltage needed to turn the neon lamps on is considerably lower and the minimum D.C. voltage which will allow the neon lamps to turn off is now higher. Under these circumstances, the difference between the two voltages, i.e. the D.C. voltage signal which must be applied, is reduced, with consequent increase in circuit stability. Within certain limitations, this reduction may be shown to be equal to the peak to peak value of the A.C. voltage.

These and other objects of the present invention together with further features and advantages thereof will become more apparent from the following detailed description in which:

FIG. 1 diagrammatically illustrates a typical embodiment of the present invention; and

FIG. 2 illustrates graphically the effect of the A.C. bias on the voltages required to drive a gas discharge tube.

In specific reference to FIG. 1, a glow transfer tube 10 is shown having therein an anode 12, a series of cathodes 14, and a series of guides 16 and 18 actuated by a pulse circuit 15. The anode 12 is connected to a constant high D.C. voltage source 20 through the anode resistor 21. The cathode resistors 22 are connected in parallel to ground, while each of the cathodes 14 has a neon lamp 24 connected thereto. All of the neon lamps 24 are connected in parallel to a D.C. bias source 26 which places them at a preselected potential. In addition to the D.C. bias source 26, an A.C. voltage source 28 places an A.C. voltage bias on each one of the neon lamps 24; the A.C. source 28 may be, for example, a sine wave generator which modulates the D.C. bias.

The effect of the A.C. voltage source 28 on the magnitude of the D.C. voltages needed to drive the neon lamps 24 is shown in FIG. 2. The minimum maintaining potential for a group of neon lamps 24 is designated as e_1 , while the maximum maintaining potential is designated as e_2 . Similarly, the minimum striking potential is designated as e_3 , while the maximum striking potential is designated as e_4 . It is seen that for reliable neon operation, i.e. to ensure that all the neon lamps 24 will be turned off and on, a D.C. voltage swing D is required which is equal to $e_4 - (e_1 - d)$ where d is a voltage increment of sufficient magnitude below the maintaining potential to extinguish the discharge. If, however, the applied D.C. drive voltages are modulated by an A.C. voltage with a peak to peak value of $2E$, all the neon lamps 24 are turned off when the D.C. drive voltage is equal to $(e_1 - d) + E$ since on some portion of the negative half cycle of the A.C. bias the drive voltage falls below the minimum maintaining potential e_1 . Such a minimum drive voltage is designated as e_5 on the graph in FIG. 2; the D.C. bias is, in practice, set at this level. Similarly, all the neon lamps 24 are turned on by a drive voltage of $e_4 - E$, since on some portion of the positive half cycle of the A.C. bias the drive voltage is equal to the maximum striking potential. Such a maximum drive voltage is designated as e_6 . It is seen, therefore, that the new required voltage swing D' is equal to $e_6 - e_5$, which is equal to $e_4 - (e_1 - d) - 2E$. This is a reduction of $2E$, the peak to peak value of the A.C. bias, over the voltage swing D previously required.

Since it is not usually desired to have any of the neon lamps 24 fired on the positive half cycle of the A.C. bias when the drive voltage is e_5 , $(e_1 - d) + 2E$ must be less than e_5 ; this means that $2E$ must be less than $e_3 - (e_1 - d)$. Similarly, to prevent any neon lamps 24 from being

turned off during the negative half cycle of the A.C. bias with drive voltage e_6 on, it is necessary that $e_4 - 2E$ (or $e_6 - E$) be greater than $e_2 - d$. This imposes the limitation that $2E$ must be less than $e_4 - (e_2 - d)$. These conditions impose a maximum limitation on the peak to peak value of the A.C. voltage. However, the D.C. voltage swing required is still reduced by a significant factor. In a typical case, a voltage swing of 30 volts is reduced to 15 volts by use of the A.C. bias with a peak to peak value of 15 volts.

The A.C. voltage in the present invention may merely be taken from a line current of 60 c.p.s. Although all the neon lamps may not strike (or turn off) in succession at such a frequency, when the counting circuit is stopped to take a reading, the proper neon lamp will light in less than 17 milliseconds (and any other improperly lit neon lamp will be extinguished). The fact that all the neon lamps do not light (or turn off) in succession is far overshadowed by the significant increase obtained in stability and reliability of proper transfers in the glow transfer tube. Moreover, the human eye does not tend to differentiate such a rapid succession of individual lamps if all were to light consecutively during the counting phase.

While the use of the A.C. biasing arrangement has been illustrated in a circuit for a glow transfer tube, nonetheless such a bias can be used in any circuit which requires that gas discharge tubes be turned on and off with a minimum voltage swing. In addition, it is not necessary that a D.C. bias voltage accompany this A.C. bias. Since, in this latter case, the gas discharge tubes are usually turned off by dropping the applied voltage to zero potential, the D.C. voltage swing is reduced only by a factor of E . It should also be noted that the use of this technique need not be restricted to gas discharge tubes; it can be applied to any non-linear device which has a negative incremental resistance, ΔR , shortly after the initial rise of its operating curve; many such devices are formed in the semiconductor field, such as tunnel diodes (where the voltage changes discontinuously with small current changes) and certain types of transistors.

Having described the invention, it is apparent that numerous modifications and improvements may be made by those skilled in the art, all of which fall within the scope of the invention; therefore, the invention herein

disclosed should be construed to be limited only by the spirit and scope of the appended claims.

What is claimed is:

1. An improved counting circuit in which a glow discharge is sequentially transferred from one adjacent cathode to the next in a glow transfer tube by a series of applied impulses comprising: a series of gas discharge tubes each connected to one of said cathodes; means for sequentially applying a drive voltage to said gas discharge tubes in response to said glow discharge; and means for applying a continuous A.C. voltage to each of said gas discharge tubes to reduce the magnitude of the drive voltage necessary to reach the maximum striking potential of said gas discharge tubes, said continuous A.C. voltage having a peak to peak value less than twice the minimum striking potential of said gas discharge tubes and not greater than the difference between the maximum striking potential and the maximum maintaining potential.
2. An improved counting circuit in which a glow discharge is sequentially transferred from one adjacent cathode to the next in a glow transfer tube by a series of applied impulses comprising: a series of gas discharge tubes each connected to one of said cathodes, said series being characterized by having a maximum and minimum striking potential and a maximum and minimum maintaining potential; means for sequentially applying a drive voltage to said gas discharge tubes in response to said glow discharge; means for applying a D.C. bias to each of said gas discharge tubes, said D.C. bias having a preselected value not less than the minimum potential required to maintain a discharge in said gas discharge tubes; and means for applying a continuous A.C. voltage to each of said gas discharge tubes, said continuous A.C. voltage having a peak to peak value not greater than the difference between said minimum striking potential and said minimum maintaining potential and not greater than the difference between said maximum striking potential and said maximum maintaining potential.
